United States Patent Office

Des. 213,317

Patented Feb. 18, 1969

213,317

FLUID DISTRIBUTION UNIT

John F. Nelson, Des Plaines, Ill., assignor to Illinois
Tool Works Inc., Chicago, Ill., a corporation of
Delaware

Filed Mar. 4, 1968, Ser. No. 10,819

Term of patent 14 years

U.S. Cl. D23—40

Int. Cl. D23—01

Fig. 1

Fig. 2

Fig. 3

FIG. 1 is a perspective view of the fluid distribution unit embodying my new design.

FIG. 2 is a top plan view thereof.

FIG. 3 is a side elevational view thereof.

The bottom is substantially plain and unornamented.

I claim:

The ornamental design for a fluid distribution unit, as shown and described.
